UNITED STATES PATENT OFFICE.

ORA D. SHAW, OF CHELSEA, ASSIGNOR TO SHAW & KAISER, OF BOSTON,
MASSACHUSETTS.

DESIGN FOR A CAP.

SPECIFICATION forming part of Design No. 23,009, dated January 16, 1894.

Application filed December 7, 1893. Serial No. 493,044. Term of patent 14 years.

To all whom it may concern:

Be it known that I, ORA D. SHAW, a citizen of the United States, residing at Chelsea, in the county of Suffolk and State of Massachusetts, have invented and produced a new and original Design for Caps, of which the following, taken in connection with the accompanying drawing, is a specification.

My design is illustrated in the accompanying perspective view.

The characteristic features of my design are the band A surmounted by a crown comparatively flat on top and octagonal in general outline, in plan, the outer edge K being

serpentine, comprising four downward loops 15 A B C D uniting four upward loops as shown.

I claim—

The design for a cap as herein shown and described.

In testimony whereof I have signed my 20 name to this specification, in the presence of two subscribing witnesses, on this 5th day of December, A. D. 1893.

ORA D. SHAW.
